UNITED STATES PATENT OFFICE.

HARRY L. DAVIS, OF GREENVILLE, MAINE.

CALK.

1,243,819.

Specification of Letters Patent. Patented Oct. 23, 1917.

Application filed July 5, 1916. Serial No. 107,669.

To all whom it may concern:

Be it known that I, HARRY L. DAVIS, a citizen of the United States, residing at Greenville, in the county of Piscataquis, in the State of Maine, have invented certain new and useful Improvements in Calks, of which the following is a specification.

My invention relates to calks for the soles of boots, shoes, mocassins, and the like, and while useful for various purposes, is more particularly adapted for the use of lumbermen in driving logs.

The object of the invention is to provide a calk which may be secured in the outer sole or heel-lift of a shoe in such manner that displacement thereof from a predetermined position is effectively prevented.

A further object of the invention resides in the provision of a metallic bearing surface for the calk so that it will not work loose as the sole or heel-lifts become worn or wet.

These objects together with other attendant advantages will be apparent as the invention becomes better understood by reference to the accompanying specification and drawings forming a part thereof, and in which like characters of reference are used to indicate like parts throughout the several views thereof.

Referring to the drawings, Figure 1 is a view partly in section showing the application of my improved calk to the outer lift of a shoe.

Fig. 2 is a perspective view of the calk.

Fig. 3 is a perspective view of the bushing.

In devices of this character, as heretofore used, it has been customary to provide the shank of the calk throughout a portion of its length with corrugations or threads adapted to engage the leather upon driving or screwing the calks into position therein. Such devices have proven unsatisfactory for the reason that if the leather becomes wet or badly worn the calks have a tendency to work loose. Metallic bushings have also been used to some extent, but no practical method of securing the bushing in position so as to most effectively coöperate with the calk and maintain the flexibility of the shoe has been conceived.

Referring now more particularly to the drawings, my invention comprises a metallic bushing or sleeve 1 adapted to be inserted

through any desired thickness of leather 2 by punching or cutting suitable openings therein. It will be apparent that the number and arrangement of these openings may be varied as desired to best adapt the shoe 60 to the use for which it is intended. The bushing 1 may be provided with a flange or head 3, and is preferably of a length slightly greater than the thickness of the leather to which it is applied, so that the 65 lower end projects below the surface thereof, to permit the formation of a collar or flange 4 in any desired manner, as by swaging or the like. By reason of this construction, the bushing is securely held in position, and 70 the edges of the openings in the leather are protected against wear and distortion, as well as the entrance of foreign matter.

After the bushings have been secured in position, the calks or points 5 are inserted 75 therein. These points may be made of any desired material and preferably have an external diameter substantially equal to the internal diameter of the bushing, so that a tight fit therewith is insured. The point is 80 provided with a head 6 of comparatively large diameter, and having a plurality of spurs 7 on the upper surface thereof. These spurs may be of any desired formation, but I have found that when pyramidal in shape 85 they readily penetrate the coöoperating layer 8 of leather and present a comparatively large bearing surface thereto so as to effectively prevent relative turning movement 90 between the parts.

From the foregoing it will be apparent that the head of the calk is securely gripped between the adjacent layers of leather, which are sewed or nailed together in any usual manner, and firmly held against the 95 flange or head of the bushing. The shank of the calk also has a large metallic bearing surface, tending to reduce wear and play to a minimum, so that the calk is always in position to most effectively prevent the 100 wearer from slipping. Due to the location of the head of the calk, accidental removal or loss thereof is prevented, while calks having a threaded engagement are likely to work loose, thereby necessitating frequent 105 repair.

The flange 4 regulates the depth to which the calks may penetrate, and also acts as an obstruction to the entrance of dirt and moisture to that portion of the leather immedi- 110

ately adjoining the calk, thereby keeping the leather in good condition.

Having thus described my invention what I claim is:—

5 1. A calk for shoes comprising a bushing adapted to be secured by flanges at each end within the lower lift of a shoe, a point passing through said bushing, a head for said point seated on one of said flanges, and
10 means on said head for engagement with the adjoining lift of the shoe.

2. A calk for shoes comprising a bushing adapted to be secured by flanges at each end within the lower lift of a shoe, a point passing through said bushing, a head for said point seated on one of said flanges, and
15

spurs on said head for engagement with the adjoining lift of the shoe.

3. A calk for shoes comprising a bushing adapted to be secured by flanges at each end 20 within the lower lift of a shoe, a point passing through said bushing, a head for said point seated on one of said flanges, and pyramid-shaped spurs on said head for engagement with the adjoining lift of the 25 shoe.

In testimony whereof, I have hereunto subscribed my name.

HARRY L. DAVIS.
